(57) **CLAIM**

The ornamental design for a sign pole advertising mounting assembly, as shown and described.

DESCRIPTION

FIG. 1 is an isometric front perspective view of the sign pole advertising mounting assembly;

FIG. 2 is a front elevational view thereof;

FIG. 3 is a rear elevational view thereof;

FIG. 4 is a top view thereof;

FIG. 5 is a bottom view thereof;

FIG. 6 is a side view thereof; and,

FIG. 7 is a side view showing the side opposite that shown in FIG. 6.

The broken lines in the Figures are for the purpose of illustrating exemplary environmental structure and form no part of the claimed design.
